HERSCHEL E. TOWER, OF CINCINNATI, OHIO, ASSIGNOR TO THE BALDWIN COMPANY, OF CINCINNATI, OHIO.

PNEUMATIC ACTION FOR GRAND PIANOS.

Application filed November 30, 1927. Serial No. 236,770.

This invention relates to improvements in mechanical musical instruments of the grand piano type, the keys of which are actuated from underneath and thru the keybed by an auxiliary action actuated by any well known type of player action.

The object of my invention is to promote accessibility, easy unitary methods of installation, quick, accurate and positive regulation of various working parts and the transmission of power from the player action as directly and freely as possible, to the piano action, particular attention being given to the novel working assembly of the component units resulting in unusual accessibility of all working regulations.

The drawings show a working application of my invention as applied to a grand piano and gives a clear conception of the relative positions of the player action unit, the auxiliary action and the piano key and action.

Fig. 1 is a cross section taken from the side. Fig. 2 is a rear view with the pneumatics, chests and parts of the finger omitted.

A grand piano having a keybed 1 has a key 2 that actuates a piano action 3 for striking a string 4 to produce a musical sound. Underneath the keybed 1 is an auxiliary action consisting of a supporting rail 5, flanges 6, levers 7, stickers 8, lugs 9 and regulating means 10. In working relation to this auxiliary action is a player action consisting of shelves 11, striking pneumatics 12, fingers 13 and regulating means 14.

In practice, these mechanisms are assembled and installed as units; i. e., the keys and piano action are installed as one unit and then the auxiliary action is installed in proper working relation to the keys 2. The player action is then installed so that the regulating means 14 is in proper relation to the lugs 9 on the stickers 8. The lugs 9 in the drawing are on separate stickers, (see Fig. 2), being alternated from note to note in the scale.

After the player action has been installed 45 the regulating means 14 are adjusted to hold sticker 8 in close contact with the key 2, allowing no lost motion and consequent loss of power at that point. The regulating means 10, working to a stop against the rail 5 are for 50 the purpose of limiting the movement of the sticker 8, which in turn will give the proper stroke or lift to the key 2. It will be seen by this arrangement that the transmission of power from the striking pneumatic 12 to the 55 key 2 is very direct and efficient.

The moving leaf of the pneumatic 12 is made of such weight as to balance the weight of the finger 13, regulating means 14, sticker 8 and correlated parts, insuring that after the 60 regulating means 14 is once adjusted the sticker 8 will always stay in close contact with the key 2.

Many modifications may be made but what I claim as my invention is:

1. In a grand piano having piano keys and piano action, a pneumatic player action and a detachable auxiliary action between the pneumatic player action and the piano keys; regulating means on the pneumatic player 70 action for adjusting the auxiliary action relative to the piano keys and regulating means on the auxiliary action for limiting the movement thereof.

2. In a grand piano having piano keys, a 75 keybed and piano action, a pneumatic player action and an auxiliary action and means for attaching the auxiliary action to the surface of the keybed between the pneumatic player action and the piano keys; regulating 80 means for adjusting the auxiliary action relative to the piano keys and regulating means on the auxiliary action for limiting the movement thereof.
